RELAY

Otho D. Grandstaff, Chicago, Ill., assignor, by
mesne assignments, to Associated Electric Laboratories, Inc., Chicago, Ill., a corporation of
Delaware

Application April 26, 1935, Serial No. 18,288

13 Claims. (Cl. 200—93)

The present invention relates in general to relays, and more in particular to polarized relays, and the object of the invention is to produce a highly sensitive and efficient relay of this character, which is economical to manufacture and adapted to a wide range of commercial applications.

The construction of the new relay will be explained hereinafter in connection with the accompanying drawing, in which Fig. 1 is a top view of the relay; Fig. 2 is a side view; while Fig. 3 is a view of the bottom of the relay, or a view of the relay rotated 180° from the position in which it is shown in Fig. 1.

15 Referring to the drawing, the various parts of the relay are all mounted on an L-shaped base or base plate 2. The leg 30 of the base plate is provided with tapped holes such as 31, whereby the relay may be mounted on an ordinary relay 20 rack by means of screws. The plate 2 is preferably of brass or other non-magnetic metal.

On the lower side or bottom of the base plate 2 are two permanent magnets 3 and 4. As shown clearly in Fig. 3, these magnets are secured against the base plate 2 by means of two clamping members 5 and 6, and four screws 7, 8, 9, and 10. These clamps and screws also should be of non-magnetic metal. The magnets are arranged with unlike poles together, as shown. The size of the 30 air gaps can be regulated by slightly loosening the screws 7—10 and then tapping the magnets into the exact position required. It will be noted that no pole pieces are used and that the magnetic circuit is continuous except for the air gaps between the opposed ends of the magnets.

On the upper side of the base plate 2 there is a coil 11, and associated parts, which will now be explained. The coil 11 is wound on a spool 34, which is secured to base plate 2 by means of two 40 brackets 12 and 13 and screws such as 14. There is an opening extending axially through the spool 34 to accommodate the core 15. The opening is just slightly larger than the core 15, so that the core is free to rotate. The core 15 is provided with 45 armatures 16 and 17, and is supported on two steel reeds 18 and 19, which in turn are clamped to the base plate 2. Explaining the core and armature construction more in detail, the core 15, and likewise armatures 16 and 17, is preferably 50 made of iron of high magnetic permeability. The core 15 is slotted at opposite ends to receive the reeds 18 and 19. Each armature comprises a slightly tapered portion of rectangular cross section reaching down into the associated air gap 55 and a cylindrical portion having an opening of

the correct size to make a tight fit when the armature is forced onto the core 15. The core 15 and the armatures and supporting reeds are assembled with the coil 11 before the latter is mounted on the base plate 2. The core 15 is placed within the opening in spool 34, and then the reeds 18 and 19 are placed in the slots in the core. The ends of the core may be slightly tapered, so that the armatures 16 and 17 can be started on. By means of a press the armatures are then forced on to 10 the core into the position shown in Fig. 2. Thus the core, armatures, and reeds are securely held together.

After assembling the coil and associated parts, the spool 34 of the coil may be mounted on the 15 base plate 2 as previously mentioned. The base plate 2 is provided with openings 35 and 36, so that the armatures 16 and 17 can pass through the base plate into the air gap between the magnets. The reeds 18 and 19 may then be secured in place.

Considering the means for securing reed 18, there is a brass block 20 secured to the base plate 2 by means of a pair of screws such as 32. This block has a semi-cylindrical recess or slot in its upper face. Above block 20 there is a block 21, which has a similar recess or slot in its lower face. When the two blocks are assembled as shown the two slots correspond and form a cylindrical opening in which are positioned two semi-cylindrical members 26 and 27, one on each side 30 of reed 18. Block 21 is secured to block 20 by means of four screws such as 37. It will be clear that by assembling the parts as explained and by then tightening up the screws 37 the reed 18 will be firmly held.

The reed 19 is clamped between members 24 and 25 by means of blocks 22 and 23 in a similar manner.

The armature 16 is just long enough to pass through the corresponding air gap. Armature 17, however, is somewhat longer, its end extending beyond the air gap, as seen in Fig. 2. Armature 17 functions as the movable contact of the relay and is provided with contact points as shown in Fig. 3.

The terminals, contact springs, and adjusting means for the contact springs are mounted on an L shaped bracket 40, which is secured to the lower side of the base plate 2 by means of screws such as 49. The leg 41 of bracket 40 stands perpendicular to base plate 2, as seen in Fig. 2. The various springs, insulators, etc., are clamped together and to the upright leg 41, by means of screws 54. These screws are threaded in member 41, whereby part of the assembly is clamped

between 41 and the heads of the screws, and extend beyond member 41 far enough to enable the remainder of the assembly to be clamped between member 41 and the nuts 55.

5 Considering this assembly more in detail, the terminal 42 is not insulated on the upper side and provides for connecting with the armature 17 which is the movable contact member. The circuit extends from terminal 42 by way of screws 10 54, bracket 48, base plate 2, block 22, and reed 19 to armature 17. In other words, the movable contact member and terminal 42 are "on the frame". The contact springs between which the movable contact member or armature 17 operates 15 are denoted by 45 and 46. These springs have a slight tension away from 17, which causes their ends to bear against adjusting springs 56 and 57, respectively. Springs 56 and 57 also are tensioned away from 17, but are held in the proper 20 position by adjusting screws 53 and 52, respectively. The latter are threaded in the comparatively stiff spring members 51 and 50, and are provided with lock nuts as shown.

The coil 11 may have any desired number of 25 windings depending on how the relay is to be used. A very useful arrangement is to provide two windings which can be connected either in series or in parallel. One winding may be connected to terminals 43 and 44 and the other to terminals 30 47 and 48. 60 and 61 are two bushed holes in base plate 2 through which conductors from the windings of coil 11 may be led to the terminals.

The utility of a polarized relay is well known. 35 In describing the operation of the present relay, therefore, it will be assumed for the sake of simplicity that it is connected to a source of alternating current, with the two windings of the relay in series. The alternating current source is connected to terminals 43 and 48, and terminals 44 40 and 47 are connected together.

With the current off, the armatures 16 and 17 45 may stand at the center of their respective air gaps. When the current is turned on, the core 15 is magnetized and the relay responds. Assuming that when first turned on the direction of current 50 is such that armature 16 becomes the north pole and armature 17 the south pole, both armatures will be attracted by magnet 3 and repelled by magnet 4. Therefore the core 15 will be rotated within coil 11 and armature 17 will make contact 55 with spring 45. The rotation takes place against the resistance of the reeds 18 and 19, which offer an increasing force opposing the movement. This opposing force, however, increases with a 60 straight line characteristic, while the magnetic force depends on the square of the distance between the magnet 3 and the armatures. As this distance decreases by rotation of the core 15 the magnetic pull will build up somewhat faster than 65 the opposing spring pressure and armature 17 will engage spring 45 with good contact pressure. The adjustment of the air gaps is such that the rotation of the core 15 is stopped by engagement of armature 17 with spring 45 before the armatures 17 and 16 reach the poles of magnet 3.

Now at this stage of the operation a considerable portion of the flux produced by magnet 3 will be diverted by the armatures through core 15. This flux will tend to hold the core in rotated 70 position as the current in the coil decreases, but is opposed by the reeds 18 and 19, which tend to restore the armatures to mid position. The point at which the armatures begin to restore depends on whether the relay is adjusted for "stay put" 75 operation or not. By this expression is meant an

adjustment such that the armatures will be held in either position by the pull of the adjacent permanent magnet alone and without current in the coil. For rapid response to alternating current such adjustment is not desirable, and in the present case therefore the adjustment will be such that some time before the current in the coil reaches zero the pressure stored in the tensioned reeds will over power the pull of the magnet 3 and the restoration of the armatures will begin. 10

After falling to zero the current in the coil will start to build up in the opposite direction, thereby reversing the polarity of the core 15 and causing armature 16 to become the south pole and armature 17 the north pole. Both armatures are 15 accordingly attracted toward magnet 4, causing armature 17 to engage spring 46. On the assumption that the relay has a symmetrical adjustment the operation on this side will be the same as described. 20

Adjustment of the relay for various operating requirements will now be explained. For the maximum sensitivity the permanent magnets should be adjusted so that the air gaps are as short as they can be without permitting the armatures to strike the poles of the magnets. The sensitivity is a function of the pull exerted by the permanent magnets. By shortening the air gaps the pull of the magnets is increased and therefore the sensitivity also. The design of the 30 relay permits very powerful permanent magnets to be used and hence great sensitivity can be secured.

If high sensitivity is to be retained and at the same time a very rapid response is desired, as 35 would be the case if the relay is to be used to respond to weak alternating currents of a frequency of perhaps 60 cycles or higher, a considerable part of the pull of the permanent magnets must be balanced out by the reeds 18 and 19. 40 These reeds can be made stiffer by decreasing their effective length, which is done by moving the clamping members 26, 27, 24, and 25 toward the core 15. Increasing the stiffness of the reeds 45 does not affect the sensitivity, because the opposition to rotation produced by the reeds is zero at mid point of the armatures no matter how stiff the reeds are. But it will be clear that increased stiffness of the reeds does speed up the response 50 of the relay because it causes the armatures to start to restore sooner on a falling current in the coil.

The extent to which the foregoing adjustment 55 can be carried out depends on the contact pressure required. This will be obvious because the contact between 17 and 45 or 46 is made by the magnetic pull against the resistance offered by the reeds. For maximum rapidity of response in any given case, the proper procedure is to calculate the minimum allowable contact pressure and 60 the minimum operating current that will be available, and then adjust the reeds as stiff as they can be and still secure the necessary contact pressure with the minimum operating current.

It will be appreciated that great rapidity of 65 response can also be secured by adjusting the magnets so as to increase the length of the air gaps, leaving the reeds with an average adjustment. This method of adjustment, however, will 70 secure increased speed of response at the expense of a somewhat decreased sensitivity.

For certain uses it is necessary that the relay have a "stay put" adjustment, which means, as previously explained, that the armatures will 75 stay in either operated position upon cessation of

current in the operating coil. This adjustment is made by shortening the air gap or decreasing the stiffness of the reeds, or both, until the desired operating characteristic is secured. The relay 5 can be biased in only one direction if desired by an unsymmetrical adjustment of the magnets. Thus if magnet 3 is moved up close while magnet 4 is moved away somewhat, the relay can be made to "stay put" with contact 45 closed but 10 not with 46 closed.

Pointing out some of the advantages of the relay, it will be clear that the relative simplicity of the design, which involves among other things the use of only a single coil, makes it a very 15 economical relay to manufacture.

The arrangement of the magnetic circuit with 20 armatures operating in two air gaps is very efficient. By using powerful magnets and balancing out part of the magnetic pull with torsional 25 springs great sensitivity and rapidity of response can be secured.

The elimination of pole pieces avoids a common 25 source of loss in other relays where such pole pieces are employed. There is always an increased reluctance in the magnetic circuit if pole pieces are employed due to impossibility of making a perfect connection between the pole pieces and the magnets.

The use of a single coil and the spaced relation 30 of this coil to the magnetic structure greatly reduces the losses which ordinarily arise from leakage flux. Consideration of the several views of the drawing will show that the coil is well removed from the magnets, due to being in a different plane and because of the spacing between the magnets, which makes all portions of the turns on the coil highly effective in producing flux in the core 15.

As mentioned before the core 15 is just slightly 35 smaller than the bore of the spool 34 in which it rotates freely without touching. Consequently air damping such as is caused by drawing in and expelling air is eliminated. This is a decided advantage over those constructions which employ a 40 vibratory armature positioned in the bore of a coil or coils. A further advantage over such constructions lies in the fact that the opening through the coil need only be enough larger than the core 15 to provide for free rotation, 45 and does not have to afford space for lateral displacement. The average distance of the coil turns from the core may therefore be decreased adding to the efficiency. The spool 34, for instance, may comprise a thin walled fiber tube 50 with the heads as shown, which brings the inner turns of the coil very close to the core.

Other advantages lie in the adaptability of the relay to different uses and the facility with which 55 its adjustments may be changed to alter its operating characteristics, together with miscellaneous features of improvement which lend desirability to a device of this character.

The invention having been described, that which is believed to be new and for which protection of Letters Patent is desired will be pointed 60 out in the appended claims.

What is claimed is:

1. In a polar relay, a magnetic circuit including 65 two air gaps, a fixed coil, a core supported for rotation in said coil, and armatures extending from the opposite ends of said core into said air gaps.

2. In a polar relay, a magnetic circuit including 70 two air gaps, a fixed coil, a core supported for rotation in said coil, an armature on one end of

said core extending into one of said air gaps, an armature on the other end of said core extending through the other air gap, and contacts adapted to be operated by the end of said last mentioned armature. 5

3. In a polar relay, an operating coil, a core within said coil, means including two reeds supporting said core for rotation within the coil, an armature attached to said core, and a magnet adjacent said armature adapted to move the 10 same and rotate the core against the tension of said reeds when the coil is energized.

4. In a polar relay, a magnetic circuit including 15 two air gaps, a coil, a core loosely fitting in said coil, means including two reeds for supporting said core for rotation, armatures extending from opposite ends of said core into said air gaps, whereby said armatures will be operated upon energization of the said coil, and means for adjusting the stiffness of said reeds so that upon 20 deenergization of the coil the said armatures will be retained in operated position or not depending on the operating characteristic desired.

5. In a polar relay, the combination with a 25 spool comprising a thin walled tube and heads 30 on opposite ends thereof, a winding on said spool, a core of magnetic material having a diameter slightly smaller than the bore of said tube, means supporting said core for rotation within said spool, and means including a magnet and an 35 armature on said core for rotating the same responsive to energization of said winding.

6. A core and armature assembly for a polar 40 relay comprising a rod of magnetic material, said rod being slotted at both ends, two reeds, one 45 inserted in each slot, and two armatures also of magnetic material, said armatures having openings therein and being forced on to the slotted ends of said core to secure the reeds in position.

7. In a polar relay, a magnetic circuit including 45 two air gaps, an armature positioned in one air gap, contacts adapted to be operated by said armature, a second armature positioned in the other air gap, means for magnetizing said armatures, whereby said first armature operates said 50 contacts, and means including a mechanical connection between said armatures whereby the second armature when magnetized delivers power to said first armature to assist the same in operating said contacts. 55

8. In a polar relay, a rotatable shaft, a magnetic 60 circuit including an air gap, a coil surrounding said shaft for magnetizing the same, electrical contacts, a lever arm attached to one end of said shaft for actuating said contacts, and an armature attached to the other end of said shaft and extending into said air gap, said armature responsive to the magnetization of said shaft to rotate the same and apply power to said lever arm.

9. In a polar relay, a base plate, a permanent 65 magnet mounted on one side of said plate, a coil mounted on the other side of said plate, a rotatable core for said coil, openings in said plate opposite the ends of said core, and armatures extending from the ends of said core through said 70 openings and into operative relation with the poles of said magnet.

10. In a polar relay, a magnetic circuit including 75 a permanent magnet and an air gap, a coil, a core extending axially through said coil, means supporting said core for rotation on the coil axis, means for rotating said core comprising an armature attached to the core outside said coil and extending within said air gap, and an electrical contact operated responsive to rotation of said core. 75

11. In a polar relay, a magnetic circuit including a permanent magnet and an air gap, a coil, a rotatable core extending through said coil and having its rotation axis coincident with the axis 5 of the coil, an armature for rotating said core, said armature comprising a crank having one end attached to said core and the other end extending within said air gap, and resilient means arranged to oppose rotation of said core.
- 10 12. In a polar relay, a magnetic circuit including a permanent magnet and an air gap, a coil, a rotatable core of which a portion lies inside said coil, the axis of the core coinciding with the axis of the coil, means for rotating said core comprising 15 a crank-like armature attached to the core and extending within said air gap, and resilient means normally maintaining said armature at a predetermined position in said air gap and offer-
- ing an increasing resistance to rotation of said core in either direction.
13. In a polar relay, two permanent magnets, means supporting said magnets with the poles of one magnet adjacent the unlike poles of the other 5 magnet but spaced away therefrom, thereby forming a magnetic circuit which includes the two magnets in series and two air gaps, a rodlike core supported for rotation, armatures for rotating said core, said armatures extending from spaced 10 points on the core into said air gaps, a coil on said core between said armatures, means supporting said coil in a fixed position where its axis coincides with the axis of said core, and electrical contacts operated responsive to rotation of said core.

OTHO D. GRANDSTAFF.
